UNITED STATES PATENT OFFICE.

FRITZ WEINBERG, OF WASHINGTON, DISTRICT OF COLUMBIA, ASSIGNOR TO EMILE BERLINER, OF WASHINGTON, DISTRICT OF COLUMBIA.

MULTICYLINDER ROTARY GAS-ENGINE.

1,105,118.

Specification of Letters Patent.

Patented July 28, 1914.

Application filed August 14, 1908. Serial No. 448,574.

To all whom it may concern:

Be it known that I, FRITZ WEINBERG, a subject of the Emperor of Germany, residing at Washington, in the District of Columbia, have invented certain new and useful Improvements in Multicylinder Rotary Gas-Engines, of which the following is a description, reference being had to the accompanying drawing and to the letters and figures of reference marked thereon.

My invention relates particularly to that class of four cycle internal combustion engines, in which a plurality of cylinders rotate about a fixed crank shaft.

15 The invention consists in the matters hereinafter described and referred to in the appended claims.

The invention is embodied in the construction illustrated in the accompanying drawings, in which,

Figure 1 is a side elevation of my improved rotary multi-cylinder internal combustion engine, apart from its base or support; Fig. 2 is an end view thereof; Fig. 3 is a central longitudinal section through one of the cylinders, showing the valve mechanism, the crank shaft and the base or support; Fig. 4 is a face view of the valve actuating cam, Fig. 5 is a sectional view thereof; and Fig. 6 is a detail view showing the connection between the valve rod and its shoe.

A, designates the base, which may be vertically or horizontally disposed, and B, is the fixed crank mounted on said base by means of its hollow trunnions b, b.

C, designates the several cylinders of which five are shown and these cylinders are connected at their inner ends to form a central chamber or crank case C', having bearing hubs c, c', which turn on the crank shaft trunnions b, b, as shown in Fig. 3, the hub c having thereon the transmission gear c² adapted to be geared to the shaft to be driven.

45 C² are the several trunk pistons provided with abutment rods C³ connected at their opposite ends in the usual way to the crank B. In the outer end of each cylinder, are provided horizontally aligned inlet and exhaust ports, D, E, respectively, which are controlled by the inwardly opening valves D', E', on the inner ends of the valve stems d, e, which extend out through the cylinder heads. The outer ends of these valve stems 55 are both slidingly pivoted to a common lever

f, by a pin and slot connection, the stem d, being pivoted to the inner end of the lever f, and the stem e, being pivoted between the ends of the lever and said lever f is pivoted between the valve stems to the cylinder head 60 at f'.

D² are passages leading to the inlet valves D from a common central chamber D³ concentric with the hubs b, b, and communicating with the outer stationary supply 65 chamber D⁴, having a supply pipe d⁴ supplied with explosive mixture from any suitable source, not shown. The supply pipe d⁴ is provided with a suitable throttle valve d⁵, see Fig. 3.

70 G, designates the valve operating rods, one for every cylinder and these rods are pivoted at their outer ends to the outer ends of the lever f and are provided within the central chamber or crank case C', with 75 springs g, which exert an inward pull or pressure on the rods. The inner ends of the rods G, are each provided with a pivoted shoe g' actuated by the cam H to be now described. The cam H, is formed of a ring 80 parallel with the plane of rotation of the cylinders, and fixed to one of the crank shaft trunnions b, as shown in Fig. 3. In the face of the cam ring H, is formed a double loop cam groove in which travel 85 the shoes g' of the valve rods G, as indicated in Figs. 4 and 5. The outer groove h, extends from the abutment h¹ around to a point about diametrically opposite to said abutment and then widens inwardly to the 90 middle flange h² which extends to the abutment where a gap h³ separates it from the flange h⁴ which extends around opposite to the abutment where it curves inwardly to the innermost flange h⁵, which curves outwardly at the abutment and joins the flange h⁴. Concentric with the outer cam groove 95 h, and forming the inner wall of its narrower portion, is a slotted flange h⁶; its slot h⁷ extending through the cam ring, (see 100 Fig. 5), to permit the cranked end k, of the operating rod K, to work therein. To the extremity of this end k is secured at one end, a segment h⁸, which slides on the slotted flange h⁶, so as to lengthen said flange h⁶, and prevent the shoe g' of the valve rod from being pressed inwardly by the spring g to the flange h² for a purpose to be presently described. The other end of the movable segment h⁸ has a guide pin h⁹ which 110

works in a groove h^{10} in the face of the cam ring and forming a continuation of the slot h^7 of the flange h^6 . This stationary cam controls both the valves of each cylinder 5 during the periods of suction, compression, explosion, expansion and exhaust, through the medium of the single operating rod G, the valve rods being successively operated.

- The operation is as follows; see Fig. 4;
- 10 The shoe g' of the upper rod G, is in the middle of the suction stroke and is traveling in the direction of the arrow. During its travel through this suction groove h , the shoe g' , is in its highest position and so holds 15 the inlet valve D' open while the exhaust valve E' is held closed. When this shoe leaves the end of the segment h^8 , the spring g , pushes the rod G and the shoe inwardly to the flange h^2 forming the upper wall of 20 the compression groove, whereupon both valves D', E' are closed by centrifugal force and are so held till the shoe passes across the gap h^3 and travels to the end of the expansion groove, formed by the flange h^4 . In 25 passing the gap h^3 at the abutment h' the explosion is effected in any well known manner at spark plugs S. After reaching the end of the flange h^4 farthest from the abutment h' , the spring g pushes the shoe g' inwardly 30 against the flange h^6 , forming the upper wall of the exhaust groove, whereupon the rod G pulls down on the rod e and opens the exhaust valve E' and holds it open till the shoe reaches the outwardly curved end of the 35 flange h^5 next to the abutment h' . At this point, the shoe switches over past the abutment to the curved end of the flange h^6 and again enters the suction groove h , whereupon the inlet valve is again opened and the 40 exhaust valve closed and the cycle of operations repeated. In order to vary the period of compression, it is only necessary to slide the compression regulating segment or tongue h^8 around in the direction of the 45 arrow in Fig. 4, which prevents the shoe g' from moving inwardly in the compression groove formed by the flange h^2 and so holds the inlet valve open for a longer period. Any gas forced out through the inlet valve 50 on the compression stroke will return to the supply chamber D' and be taken in on the suction stroke of the next piston. This renders starting the engine quite easy and the speed of the engine may be governed by this 55 same compression segment if desired. On opposite sides of the cylinders are formed or secured the obliquely disposed longitudinal fan blades I; the blades of one cylinder being in the same plane and parallel to those 60 of the next, and all of the blades projecting beyond the sides of the cylinders. It follows that the fan thus formed will cause the air to be drawn in rapidly at one side of the

rotary engine and discharged at the other side after passing across the cylinders and 65 effectually cooling them. Water cooling is thus avoided. The fan blades I furthermore, act as heat radiating ribs, and assist thus in a further cooling of the cylinders.

Having thus particularly described my invention, what I claim as new and desire to secure by Letters Patent, is:

1. The combination with a fixed crank, a plurality of cylinders rotating about the crank, pistons in the cylinders connected 75 with the crank, inlet and exhaust valves on the outer ends of the cylinders, and an operating rod for every cylinder connected at its outer end to the inlet and exhaust valves of its cylinder, of a fixed double loop cam 80 parallel to the plane of rotation of the cylinders and provided with inner and outer cam grooves in its face, a circularly movable segment on the face of the cam for lengthening the outer groove to regulate the time of compression, and shoes on the inner ends of the valve rods traveling in said grooves as the cylinders rotate to actuate the valves during the periods of suction, compression, explosion and exhaust. 85

2. The combination with a fixed crank, of a plurality of cylinders rotating about the crank, pistons in the cylinders connected to the crank, inlet and exhaust valves in the cylinder heads, levers pivoted between their 95 ends to the cylinder heads and having loose pivotal connections with the stems of the inlet and exhaust valves, valve rods on the cylinders pivotally connected at their outer ends to the outer ends of the said levers and springs on the valve rods pressing them inwardly, of a fixed double-loop cam parallel with the plane of rotation of the cylinders and having cam grooves in its face and a circularly movable segment on its face to 100 lengthen the inner wall of the outer groove of the cam to vary the compression, and pivoted shoes on the inner ends of the rods traveling around in the said grooves as the cylinders rotate, to actuate the valves during 110 the periods of suction, compression, explosion and exhaust.

3. In an internal combustion engine, a valve controlling cam comprising a ring having grooves in its face to control the suction, compression, explosion and exhaust periods, and a circularly movable segment on the face of the cam and forming the inner wall of the suction controlling groove to vary the compression period. 115

In testimony whereof I affix my signature, in the presence of two witnesses.

FRITZ WEINBERG.
